UNITED STATES PATENT OFFICE.

JOHN H. BURKHOLDER, OF ASHLAND, OHIO.

DESIGN FOR A DOOR-HANGER TRACK.

SPECIFICATION forming part of Design No. 34,103, dated February 19, 1901.

Application filed January 18, 1901. Serial No. 43,813. Term of patent 7 years.

To all whom it may concern:

Be it known that I, JOHN H. BURKHOLDER, a citizen of the United States, residing at Ashland, in the county of Ashland and State 5 of Ohio, have invented and produced a new and useful Design for Door-Hanger Tracks, of which the following is a specification.

My invention relates to a new and useful design for a door-hanger track; and it consists of a track of the configuration and ornamentation shown in the accompanying drawings, in which—

Figure 1 is a front view of a section of the track. Fig. 2 is a rear view, and Fig. 3 is an 15 end view thereof.

The leading feature of my design consists of a plate A, substantially parallelogram in form, having at one end a curved projection B of a diameter less than the width of the 20 plate and at the other end a corresponding curved aperture C, which plate A is engaged with brackets D and E, which project upon either side beyond the plane of the plate A and protrude through the plate A, showing

riveting-surfaces F and G. The brackets D 25 and E have upon one side perforations H and I and upon the other J and K and L and M, by means of which they are adapted to be bolted to the supporting-frame. The brackets have upon their under side substantially 30 V-shaped apertures N and O, corresponding to the configuration of the exterior of the brackets.

These door-hanger tracks are sold to the trade in sections and are adapted to be joined 35 together and to be used in conjunction with a door hanger or carrier.

What I claim is—

The design for a door-hanger track herein shown and described. 40

In testimony whereof I have hereunto set my hand in the presence of two subscribing witnesses.

JOHN H. BURKHOLDER.
